HOLDER FOR A MOP, BROOM OR THE LIKE

Ralph G. Sanders and Norman B. Watkins, Burbank,
Calif., assignors to Technibilt Corporation, Glendale,
Calif., a corporation of California

Filed Sept. 28, 1962, Ser. No. 71,915

Term of patent 7 years

(Cl. D9—2)

The fragmentary broken line showing of a handle in FIGURES 1, 2, and 3 is for the purposes of illustration only.

We claim:

The ornamental design for a holder for a mop, broom or the like, substantially as shown and described.
